CLAIM

The ornamental design for a flag safety device, as shown and described.

DESCRIPTION

FIG. 1 is a perspective view of a flag safety device showing my new design;

FIG. 2 is a front view of the flag safety device of FIG. 1; FIG. 3 is a rear view of the flag safety device of FIG. 1; FIG. 4 is a left-side view of the flag safety device of FIG. 1; FIG. 5 is a right-side view of the flag safety device of FIG. 1;

FIG. 6 is a top view of the flag safety device of FIG. 1; FIG. 7 is a bottom view of the flag safety device of FIG. 1; FIG. 8 is a front view of the flag safety device of FIG. 1 shown positioned on a vest;

FIG. 9 is a perspective view of the flag safety device of FIG. 1 in its fully extended form shown positioned on a vest; FIG. 10 is a rear view of the flag safety device of FIG. 1 shown positioned on a vest;

FIG. 11 is a front view of the flag safety device of FIG. 1 showing the flag in a vertical position with respect to the vest; and,

FIG. 12 is a rear view of the flag safety device of FIG. 1 showing the flag in a vertical position with respect to the vest.

The broken lines in FIGS. 8-12 depicting a vest represent environmental subject matter that forms no part of the claimed design. The additional broken lines in the figures depict stitching and form no part of the claimed design.

1 Claim, 10 Drawing Sheets
